AIR CIRCULATING ATTACHMENT

John J. Juby, Jr., Marblehead, Ohio

Application August 14, 1940, Serial No. 352,610

2 Claims. (Cl. 126—109)

The present invention relates to an air circulating attachment for stoves and furnaces and more especially to furnaces of the hot air type.

An important object of the invention resides in the provision of an attachment including a blower that will draw in relatively cold air from the exterior of the stove or furnace and feed the same through a tube heated by the stove or furnace where it mixes with and is expelled with the hot air produced by the stove or furnace.

Another object of the invention is to provide a heating coil positioned in or around the combustion chamber of a heating device and means for feeding relatively cold air thereto to be heated therein to be expelled with the heated air of the combustion chamber.

The invention also consists in certain other features of construction and in the combination and arrangement of the several parts, to be hereinafter fully described, illustrated in the accompanying drawing and specifically pointed out in the appended claims.

The figure is a vertical sectional view of a stove equipped with the air circulating attachment, parts thereof being shown in elevation.

Referring to the drawing for a more detailed description thereof, in the figure there is disclosed a heating stove of conventional construction that is generally designated by the reference numeral 5 which includes an outer casing 6, a combustion chamber 7, and fire-box 8. The casing rests upon a base 9 and the upper end of said casing is provided with a multiplicity of openings 10 through which heated air is expelled. An outlet pipe 11 projects from the combustion chamber 7 for carrying off waste gases, said pipe being suitably connected with the combustion chamber in a manner well known in the art.

An angularly disposed air duct 12 is formed in the combustion chamber adjacent the upper end thereof and communicates with the central outlet 13 through which heated air is expelled for discharge through the openings 10.

The air circulating attachment includes a blower 14 mounted in the casing 6 near the bottom end thereof for drawing in cold air from the exterior of the furnace. The blower is attached to the casing by means of a plate 15 and the outlet end 16 of the blower is attached to a flexible tubing 17. The tubing 17 is coiled around the lower section of the combustion chamber as indicated at 18 and extends upwardly around the casing with its opposite end 19 entering the air duct 12 and terminating in a flange coupling 20 within the outlet 13. The heat of the combustion

chamber maintains the tubing 18 in a heated condition so that as air is circulated therethrough it becomes intensely heated prior to its discharge through the end 19 into the outlet 13. The area between the combustion chamber 7 and the casing 6 is also heated and a certain amount of cold air will be drawn in through the inlet opening 21 to be heated and discharged through the openings 10. A certain amount of the air entering the opening 21 will be directed into the duct 12 since said duct is open at opposed sides of the combustion chamber.

The blower 14 is controlled from a thermostat generally designated by the reference numeral 22, said thermostat being of the type including a switch adapted to be actuated for operating the blower as the temperature drops and rises.

Thus it will be seen that in the invention shown in the figure, cold air which is present on the floor and around the casing 6 will be fed through the tubing 18 where it is heated by the combustion chamber and discharged into the room. A vacuum will be created adjacent the upper end of the combustion chamber for drawing the air through the opening 21 to be heated in the space between the combustion chamber and the wall of the casing, the flow of the heated air being indicated by the arrows.

Also it will be understood, of course, by those skilled in the art that variations in the hereinabove described device involving the substitution of substantial equivalents for the devices described are intended to be comprehended within the spirit of the present invention and that the invention is capable of extended application and is not confined to the exact showing of the drawing nor to the precise construction described and, therefore, such changes and modifications may be made therein as do not affect the spirit of the invention nor exceed the scope thereof as expressed in the appended claims.

What is claimed is:

1. In a hot air heating device, comprising a casing having air inlets at one end and outlets at the opposite end, a combustion chamber mounted within the chamber and spaced therefrom, obliquely arranged passages extending upwardly through the combustion chamber and communicating at their lower ends with the space surrounding the combustion chamber and communicating with a central passage in the firepot, a tubing coiled around the combustion chamber, a blower for forcing the air into the lower end of the tubing and the upper end of the tubing extending through one of the obliquely arranged

passages and having an open upper end communicating with the central passage.

2. In a hot air heating device, comprising a casing having air inlets and outlets at opposite ends, a combustion chamber mounted within the casing and spaced therefrom, obliquely arranged passages extending upwardly through the combustion chamber and in the combustion chamber at their lower ends with their lower ends communicating with the space surrounding the com-

bustion chamber and having their upper ends communicating with a central passage in the combustion chamber, a tubing coiled around the combustion chamber and having its lower end extending through the casing, a blower connected to said tubing, the upper end of the coil extending through one of the obliquely arranged passages and terminating in the central passage.
